SYSTEM AND APPARATUS FOR FLOWING
WELLS

Jeddy D. Nixon, Houston, Tex., assignor of one-half to Wilson Supply Company, Houston, Tex., a corporation of Texas

Application November 9, 1940, Serial No. 365,024

32 Claims. (Cl. 103—232)

This invention relates to new and useful improvements in systems and apparatus for flowing wells.

One object of the invention is to provide an improved system and apparatus including an automatic or pressure differential operated valve, which while operated by a pressure differential is so controlled as to make for economical, as well as efficient and profitable, use of the lifting fluid, which usually is gas.

It is pointed out that the larger portion of all wells fluctuate and vary in the quantity of fluid produced, the constituency or composition of the produced fluid and the rate at which the wells produce their fluids. Also, the components or composition of the well fluid, as well as the amount of fluid allowed to be produced, are factors in determining the various producing conditions encountered. In producing fluid from a well with a pressure or a lifting fluid, the lifting fluid is stored or maintained in an annular space, usually the well casing, and the amount of pressure of the lifting fluid maintained generally determines the quantity of well fluid that may be lifted. The length of the flow line from the usual casing head to the storage tanks or other suitable disposal determines the back pressure that is placed on the fluid traveling through said flow line and in said well tubing. The longer the flow line is, the greater the back pressure that is set up and this back pressure affects to some extent the lifting of the well fluid.

It is possible with applicant's invention to vary the pressure of the lifting fluid maintained in said well casing to control the amount of the fluid lifted, the intervals at which it is lifted and the velocity of the lifted fluid. However, any change in the weight of the well fluid due to variance in the composition of said fluid does not affect the operation of the inlet valve nor the surface control mechanism. Although, the different constituents of the well fluid encountered in various installations will affect the setting of the surface control mechanism.

It is also possible to change the pressure differential of applicant's fluid inlet valve to obtain the desired opening pressure in order to increase or decrease the velocity of the lifted body or "slug" of well fluid flowing up the tubing and through the flow line. Furthermore, by changing the opening or operating pressure of the surface control apparatus, different weights and lengths of slugs may be satisfactorily handled, as well as the different back pressures that are set up by the

various lengths of flow lines and other operating conditions.

A particular object of the invention is to provide an improved well flowing system and apparatus whereby more uniform flow or periodic discharges of maximum amounts of well fluid are obtained with substantially equal amounts of lifting fluid, thus preventing waste of lifting fluid.

A further object of the invention is to provide for an accumulated column of well fluid, sufficient to assure a pay load of well fluid at each admission of lifting fluid, by maintaining such admission closed until a column of well fluid of the desired amount is built up.

Another object of the invention is to provide an apparatus of the character described wherein the lifting fluid inlet valve is positively opened and closed by spring action, thus preventing sticking of the valve.

Still another object of the invention is to provide a system and apparatus wherein the lifting fluid admitting valve is set to open on a predetermined pressure differential and to be positively closed when a desired quantity or a predetermined pressure of well fluid reaches the top of the well.

A further object of the invention is to provide an improved lifting fluid inlet valve which may be used as a kickoff valve, a flow valve, or a bottom hole valve.

An important object of the invention is to provide a surface operating device having valve fastening and releasing means also arranged to close the valve, and including an operator on the surface adapted to be actuated by the well fluid that is elevated by the lifting fluid.

Still another object of the invention is to provide a system and apparatus wherein the flow of the well fluid is utilized to operate surface equipment which has such connection with one or more lifting fluid admitting valves in the tubing, as to positively close such valves after a sufficient quantity of lifting fluid has been admitted, by each valve, to carry out the desired lifting or elevating operation.

Still another object of the invention is to provide an improved fluid inlet valve that may be so arranged that adjustments may be made to obtain various opening pressures in order to increase or decrease the velocity of the lifted well fluid, whereby the opening pressure may be predetermined and set to handle the well fluid in accordance with the well conditions of the particular installation.

It is an important object of the invention to provide an improved well flowing system and ap-

paratus whereby the pressure of the lifting fluid may be varied to regulate the amount of well fluid lifted, the velocity of the lifted well fluid, the intervals at which the well fluid is lifted, and to produce the well fluid from a low standing fluid level.

A further object of the invention is to provide a system and apparatus so arranged that when the well is flowing or producing the well fluid naturally, that is, without the admission of lifting fluid, the lifting fluid admitting valve or valves are maintained closed and the waste of lifting fluid is prevented.

A particular object of the invention is to provide a system which may be used as satisfactorily on an open well, without the use of the usual packer as shown in the drawings, or on a closed well, where a packer is used in the well.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a view, partly in elevation and partly in section, showing the upper portion of a well with a well fluid lifting apparatus, constructed in accordance with the invention, connected thereon;

Figure 2 is a continuation of Figure 1, partly in section and partly in elevation, showing the lower portions of the well casing and the tubing string with a pressure fluid inlet valve, constructed in accordance with the invention, mounted in said tubing and the operating device therefor; said valve being closed and fastened against automatic actuation;

Figure 3 is a view, partly in section and partly in elevation, showing the upper portion of a well with another form of surface operating means;

Figure 4 is a continuation of Figure 3, similar to Figure 2, and showing the valve released and in position for automatic operation;

Figure 5 is an enlarged, vertical, sectional view of the automatic valve released and opened for the admission of lifting fluid;

Figure 6 is a horizontal, cross-sectional view taken on the line 6-6 of Figure 5;

Figure 7 is a transverse, vertical, sectional view of the pressure fluid control valve for the mechanism shown in Figure 3;

Figure 8 is a partial horizontal, cross-sectional view taken on the line 8-8 of Figure 5;

Figure 9 is a similar view taken on the line 9-9 of Figure 5; and

Figure 10 is a horizontal, cross-sectional view taken on the line 10-10 of Figure 5.

In the drawings, the numeral 10 designates the usual well casing which may be placed in the well bore in any suitable manner and in accordance with the conditions present at the particular well which it is desired to automatically flow. A suitable casing head 11 is mounted on the upper end of the casing 10 in accordance with the practice now in common use, and this head is provided with a pressure fluid inlet pipe 12 in which a cut-off valve 13 is connected. A single string of well tubing 14 is suspended or hung in the casing head 11 in any suitable manner and extends above said casing so that a T 15 may be connected therein. A well fluid discharge pipe 16 leads from the T and has a cut-off valve 17 connected therein.

In Figures 2 and 4, I have shown the tubing 75

string 14 extending below the casing into the shot hole A and having a perforated bull plug or strainer 18 screwed onto its lower end, but it is to be understood that the tubing may be terminated at any desired point and its relation to the lower end of the casing may be varied to suit the different well conditions encountered. It is customary to perforate casing to admit the well fluid from the formation and also to use liners and elongated screens. Any of these devices may be employed in connection with the invention.

One or more valve nipples or bodies 19, each constituting a mounting for an automatic valve, may be connected in the tubing at any desired elevation. It is customary to connect these valves in said tubing 14 at different elevations, using the uppermost valve as a kick-off valve; however, it is within the scope of the invention to use a single valve as both a kick-off valve and a flow or lifting fluid inlet valve.

The nipple 19 is provided at each end with reduced, externally screw-threaded pins 20. These pins are screwed into reducing, connecting collars 21 which in turn are screwed onto the ends of the adjacent tubing sections 14. The nipple 19 has an axial bore 22, which is smaller in diameter than the bore of the tubing, and these pins 20 are beveled at 23 at each end of the bore 22, so as to guide tools and other appliances into said bore. In order to provide ample flow space, ducts 24 are provided longitudinally of the nipple on each side of the bore 22 thereof, as is best shown in Figure 6.

One side of the nipple 19 is cut out to form a vertical recess 25, and an upright valve casing or housing 26 is mounted in this recess so as to engage snugly between the shoulders 27 formed at the lower and upper ends of said recess. This valve casing may be secured in the recess in any suitable manner so that it may be removed, if necessary. It is common practice to bolt such structures, and the valve casing may be bolted to the nipple 19 and these bolts are removed when it is desired to remove said casing 26. This casing has an inlet chamber 28 at its lower end provided with radial perforations 29, whereby the lifting fluid from the well casing may freely enter said chamber. The top of the chamber is formed by a transverse partition 30 above which overhangs an ear 32, formed integral with the valve casing 26.

The casing 26, as shown in Figures 6, 8 and 9, may be given a nearly semi-circular shape. The lower end of said casing is closed and provided with a screw-threaded and counterbored opening 31 for receiving a plug 33. The partition 30 is provided with a valve seat 34 suitably beveled to receive a valve head 35 mounted on the lower end of a valve stem 36, that extends upwardly through the seat 34, and also through the ear 32 which forms a guide therefor. The upper end of said valve stem is reduced to form a pilot pin 37 which telescopes into a socket 38 in a cap nut 39 screwed into the upper end of the valve casing.

At the lower end of the pilot pin, the valve stem is formed with a shoulder 40 for receiving a collar 41 which supports the lower end of a coiled spring 42, the upper end of which engages the under side of the nut 39. This spring is a relatively light one and is under a moderate compression. Just below the shoulder 40, the valve stem is provided with screw threads 43 for receiving a stop nut or collar 44. This collar is provided with a set screw 46 (Figure 10) which engages in a key groove 47 in the valve stem, whereby said

collar is held against rotation. A sleeve 45, slidably mounted on the valve stem, has its upper end bearing against the collar. A coiled spring 48 is confined between the lower end of the sleeve 45 and the upper side of said ear 32. This spring is considerably heavier than the spring 42 and is under greater compression, so as to force the sleeve upwardly into engagement with the stop collar, and to hold the valve head 35 on its seat 34.

The sleeve 45 is provided with diametrically opposite slots 49 which receive the yoke 50 of a bell crank lever 51, as is best shown in Figures 2, 4, 5 and 8. The lower end of the lever 51 is pivoted between ears 52 provided on the back wall of the recess 25 on each side of a vertical slot 53 communicating with the bore 22 of the nipple 19. The upper end of the lever has a small roller 54 journaled therein. When the bore 22 of the nipple is unobstructed as in Figure 2, the lever 51 is free to swing through the slot into said bore, and this will be its position when the valve is closed; the spring 48 being under sufficient compression to raise the sleeve 45 and swing the lever 51.

As hereinbefore pointed out, one of the objections to the ordinary automatic valve, which is employed for admitting lifting fluid to the well tubing, is that there is no positive way of controlling the opening and closing of said valve, and particularly the latter. It will be obvious that when the valve is closed, as shown in Figure 2, and the sleeve 45 is elevated so as to engage the collar 44, the spring 48 will not be under as great compression as it will be when the lever 51 is swung outward and the sleeve moved downwardly from said collar, as shown in Figure 4. When the lever is in the position shown in Figure 2, the valve is fastened or held against operation; whereas, when the lever is swung outwardly and the sleeve moved downwardly, as in Figure 4, the valve is released for automatic or pressure differential operation.

In order to fasten and release the valve, a suitable operating device must be provided for the lever 51. I have illustrated a cylindrical, operating bar 55 which has a snug sliding fit in the bore 22 of the nipple 19. The ends of this bar are beveled so that it will freely enter the nipple, and also ride upon the roller 54. The bar is suspended by a wire line or other flexible connection 56, and has hanging from its lower end a rod 57 which supports a weight bar 58 which latter contacts with the bar 55 in holding the wire line taut, as well as assuring a proper lowering of the bar 55. Any suitable means may be employed to raise and lower the operating bar 55. When said bar 55 is raised to the position shown in Figure 2, the lever 51 will be freed and permitted to swing through the slot 47 into the bore 22. In this position the valve will be fastened against operation.

When the operating bar 55 is lowered, the lower end engages the roller 54 and as the lowering is continued the lever 51 is swung outwardly, whereby its yoke 50 is swung downwardly. The downward swing of the yoke 50 slides the sleeve 45 downwardly on the valve stem 36, whereby said sleeve is moved away from the stop collar 44 and further compresses the spring 48, bringing the parts to the position shown in Figure 4. In this position the valve is unlocked, released, or set and ready to be operated. When a pressure differential is built up, by the hydrostatic head of oil or well fluid standing in the tubing 14, which combined with the expansive force of the upper spring 42 is sufficient to overcome the force of

the lifting fluid exerted against the valve head 35, said head will be quickly opened. When this occurs, the valve head 35 and valve stem 36 will be moved downwardly until the collar 44 engages the sleeve 45, as is shown in Figure 5.

In the preferred form of operation, the casing 10, above the fluid level standing therein, is filled with a lifting fluid which is constantly maintained under a head pressure sufficient, when admitted to the tubing, to elevate the body of oil which is picked up thereby, to the top of the tubing. It is pointed out that by this arrangement the chamber 28 is at all times maintained full of lifting fluid under the aforesaid pressure; and thus, when the valve head 35 is opened, the lifting fluid will be immediately admitted in such volume, and under such pressure, as to pick up the oil standing above the valve and carry it to the top of the tubing at a sufficient velocity to prevent slippage, or the lifting fluid channeling through the oil. In order to permit the lifting fluid to freely enter the ducts 24 of the nipple 19, a manifold 59 is provided in the bore 22 so as to communicate with the slot 47.

For raising and lowering the wire line 56, I provide an operator 60 on the upper end of the tubing 14 above the T 15, as is clearly shown in Figure 1. This operator includes a cylinder 61 in which is mounted an annular piston 62 carrying a polish tube 63 which has a snug sliding fit in the collar 64 mounted on the upper end of the cylinder. A stuffing box 65 of suitable construction is mounted on the upper end of the tube 63 by a coupling collar 66. The wire line is suspended from a clamping block 67 which is seated in a thimble 68 screwed onto the upper end of the stuffing box. It will be seen that as the piston is moved up and down in the cylinder, the polish tube 63 will raise and lower the clamping block 67, whereby the wire line 56 will be raised and lowered and the bar 55 thereby operated.

The piston 62 is designed to be operated by the well fluid which is discharged into the cylinder 60 when said well fluid is elevated in the tubing 14. The upwardly flowing well fluid will, of course, escape by way of the T 15 and pipe 16, but it will also elevate the piston, thus raising the operating bar 55 (Figure 2) and freeing the lever 51. This permits the spring 48 to expand and slide the sleeve 45 upwardly, whereby the valve head 35 will be closed. By such a means the admission of lifting fluid is positively cut off and waste prevented. It is pointed out that whenever the well fluid is flowing, the piston will be raised and all inlet or flow valves will be closed, because the spring 48 is of sufficient strength to compress the spring 42, after the lever 51 has been released by the bar 55. From this, it will be obvious that the closing of the valve is controlled by the elevation of the piston and the removal of the operating bar 55 from the path of the lever 51, so that whenever the piston is elevated by the lifted or the flowing well fluid, the operating bar 55 will be withdrawn and the spring 48 will elevate the sleeve 45, whereby the lever 51 will be swung inwardly to the position shown in Figure 2, and the valve thus positively closed and fastened against operation.

It is important to properly calibrate the springs 42 and 48. It is obvious that fluid pressure in the casing must be considerably greater than the hydrostatic head or back pressure of the well fluid in the tubing above the valve, in order to assure proper lifting of the well fluid. The spring 42 must provide the additional force necessary to

kick open the valve when the hydrostatic head of the column of well fluid, which has accumulated in the tubing, reaches a predetermined degree. The spring 48 must exert sufficient force to resist the expansive force of the spring 42 and swing the lever 51 outwardly after the removal of the bar 55.

As the pressure in the tubing 14 and flow line 16 is reduced, the pressure in the cylinder 61 and polish tube 63 will be reduced, which permits said polish tube 63 to be lowered and carry the wire line 56 therewith. As this reduction takes place, the actuating bar 55 will again be lowered into the valve body 19, swinging the roller 54, lever 51 and sleeve 45, as shown in Figure 4, which unlocks, releases or sets said valve for automatic operation. The well may be operated from this particular valve, or the actuating bar may be dropped to a lower valve, where the above operation is again carried out. It will be seen that a semi-automatic valve is thus had and a control unit therefor, which only will admit lifting fluid when there is a sufficient column of well fluid to be lifted and that the admission of lifting fluid is terminated as soon as the lifted charge or "slug" has sufficient lifting fluid therebeneath to carry it through the flow line 16 to a storage tank, or other suitable disposal (not shown).

It is pointed out that the spring 48 is much stronger than the spring 37, so that whenever the bar 55 releases the roller 54, said spring 48 will lift the sleeve 45, swinging the lever 51 and the roller 54 inwardly. The upper end of said sleeve will already be in engagement with the under side of said stop collar 44 (when said valve head 35 is opened, said stop-collar will drop down on said sleeve) and the valve stem 36 will be lifted and the valve head 35 seated on its seat 34 to close the port 30 and shut off the admission of additional lifting fluid from said casing 10 into said tubing 14.

Attention is called to the fact that the spring 37 is set for a predetermined compression in order that a pressure differential may be had between the column of well fluid in the tubing and the lifting fluid in the casing. Therefore, the weight or pressure of the column of well fluid plus the compression of the spring 37 is the operating pressure to open the valve 19, when said bar is in said valve to unlock or release the same for actuation. When the pressure of the column of well fluid plus the compression of said spring 37 becomes greater than the pressure of the lifting fluid in the casing, the valve head 35 will be moved downwardly away from its seat 34 to open the port 30, whereby lifting fluid will be admitted to expel said column of well fluid. Thus, by using different springs 37 of different compressions, various differentials or lengths of columns of well fluid may be had and various adjustments may thus be obtained in accordance with the well conditions encountered.

A further adjustment or control of the production from the well may be obtained by varying the pressure of the lifting fluid in the casing. The spring 37 when installed, is known to have a predetermined compression to set up a certain pressure differential and by increasing or decreasing the pressure of the lifting fluid, a number of results may be had. These are: first, the quantity or length of the column of well fluid may be controlled so that a greater or smaller amount of well fluid will accumulate before the valve head 35 is opened; second, the velocity or speed of flow up the tubing of the cut off column or "slug" of

well fluid may be regulated; third, the intervals at which the slugs of well fluid are lifted may be spaced farther apart or closer together; and fourth, where wells produce fluid slowly or not very high in the tubing, termed low fluid level wells, this low fluid level or short column of well fluid may be handled or lifted readily and more economically by reducing the lifting fluid pressure in the casing. These four results usually will handle any producing or well condition presented, either with or without changing the compression of the spring 37. However, in some instances the adjustment of said spring compression may be required in addition to varying the lifting fluid pressure in the casing.

Another operating apparatus is shown in Figures 3 and 7. Instead of the T 15, a cross 15' is mounted on the upper end of the tubing 14, and a nipple 70 is screwed into the top of the cross, while the well fluid discharge pipe 16 is screwed into one side of said cross. A stuffing box 71 is mounted in the nipple 70, and the wire line 56 extends through this box and is suspended from a clamp 72 mounted on the bottom of a piston rod 73 which depends from a piston 75 mounted in a cylinder 76. The cylinder is suspended by a hook 77 from the bottom of a sheave 78 which has a pulley 79 therein over which the wire line 56 passes. When it is desired to manipulate the wire line independently of the operating apparatus, the clamp 72 may be loosened to free the line which may then be operated from the sheave 78.

A T 80 is connected in the pressure fluid supply line 12 in advance of the valve 13, and a by-pass pipe 81 extends from the T to a valve body 82. As is shown in Figure 7, the valve body has a seat 83 for receiving on its upper side a valve head 84 which is mounted on the upper end of a stem 85. The valve structure is similar to an ordinary spring-loaded diaphragm valve. A supply pipe 74 leads from the valve to the bottom of the cylinder 16 for supplying pressure fluid to the cylinder to elevate the piston 75 when the valve 84 is lifted from its seat. The supply of pressure fluid is sufficient to lift the piston 75 and thereby raise the wire line, similar to the piston 62. When the valve head 84 is seated, the pressure fluid therebeyond is trapped and such pressure fluid may bleed back through a T-shaped passage 86 in a plug 87 screwed into the top of the valve 82; and thus escape to the atmosphere. As the trapped pressure fluid is bled off, the piston 75 is lowered, thereby lowering the operating bar 55. By regulating the size of the passage 86, the rate of descent of the piston may be controlled and the releasing of the valve head 84 thereby timed, if desired.

The valve stem 85 extends through a stuffing box 88 carried on the bottom of the valve body 82 which also carries a cage 89. This cage is mounted on a diaphragm bowl 90 into which is screwed a nipple 91, extending from a T 92 connected to a pipe 93 extending from the cross 15. The other end of the T is closed by a plug 94.

A diaphragm 95 is confined on the bowl by a retaining ring 96. The valve stem 85 extends through the diaphragm and a disk 97 mounted on the upper side of the diaphragm, and these parts are fastened together by nuts 98. A coiled spring 99, resting on the disk, is confined by a cross-head 100. Whenever the elevated well fluid exerts sufficient pressure on the diaphragm 95 to overcome the compression of the spring 99, the valve head 84 will be lifted and pressure fluid

thus admitted to the cylinder 76; whereby the piston 75 will be raised and the operating bar 55 elevated to permit the lever 51 to swing into the nipple 19, thereby raising the sleeve 45 and closing and fastening the automatic valve.

Various changes, alterations and modifications may be made in the size, shape and arrangement of the herein-described elements, within the scope of the appended claims.

What I claim and desire to secure by Letters Patent is:

1. The system of flowing wells which includes, a casing provided with a supply of lifting fluid, a single string of tubing, a lifting fluid inlet valve mounted in the tubing for admitting lifting fluid from the casing to the tubing, and means controllable from the top of the well for locking said valve, said means being adapted to unlocking said valve, said valve having elements responsive to pressure differentials between the well fluid and the lifting fluid and operable when the valve is unlocked.

2. The system as set forth in claim 1 with means at the surface above the well responsive to the well fluids flowing up the tubing for operating said locking and unlocking means.

3. As a new article of manufacture, an inlet valve for a well fluid lifting system which includes, a housing having a fluid inlet and a fluid outlet, a valve seat in the housing between said inlet and outlet, a valve member engaging said seat, a valve operating element mounted in the housing and projecting therefrom, a spring-impelled element mounted in the housing and operatively associated with the valve member and connected with the operating element and movable therewith, whereby said spring-impelled element functions to fasten and release said valve, and a stop on the valve member co-acting with said spring-impelled element.

4. As a new article of manufacture, an inlet valve for a well fluid lifting system which includes, a housing having a fluid inlet and a fluid outlet, a valve seat in the housing between said inlet and outlet, a valve member engaging said seat, a valve operating element mounted on the housing and projecting therefrom, a spring-impelled element mounted in the housing and operatively associated with the valve member and connected with the operating element and movable therewith, whereby said spring-impelled element functions to fasten and release said valve, a stop on the valve member co-acting with said spring-impelled element, and a nipple adapted to be connected in a tubing string provided with a mounting for the valve housing and having a bore into which the projecting portion of the operating element extends, whereby fluid flowing through the valve seat in said housing from said inlet enters the bore of said nipple.

5. The system of flowing wells which includes, a tubing string, an automatic pressure fluid inlet valve mounted in the tubing and normally responsive to a pressure differential between the well fluid and the lifting fluid to admit fluid into said tubing, and means controlled and actuated from the top of the well for fastening said valve against such differential operation.

6. The system of flowing wells which includes, a tubing string, an automatic pressure fluid inlet valve mounted in the tubing and normally responsive to a pressure differential between the well fluid and the lifting fluid to admit fluid into said tubing, means controlled and actuated from the top of the well for fastening said valve against

such differential operation, and means responsive to the pressure of the well fluid for operating said fastening means.

7. The system of flowing wells which includes, a tubing string, an automatic pressure fluid inlet valve mounted in the tubing and normally responsive to a pressure differential between the well fluid and the lifting fluid to admit fluid into said tubing, means for fastening said valve against operation and for releasing said valve for such differential operation, and means responsive to the pressure of the well fluid elevated in the tubing for operating said fastening and releasing means.

8. The system of flowing wells which includes, a tubing string, an automatic pressure fluid inlet valve mounted in the tubing and normally responsive to a pressure differential between the well fluid and the lifting fluid to admit fluid into said tubing, means for fastening said valve against operation and for releasing said valve for such differential operation, a tool movable vertically in the tubing for controlling the operation of said fastening and releasing means, and means responsive to the pressure of the well fluid elevated in the tubing for operating said tool.

9. The system of flowing wells which includes, a tubing string, an automatic pressure fluid inlet valve mounted in the tubing and normally responsive to a pressure differential between the well fluid and the lifting fluid to admit fluid into said tubing, means for fastening said valve against operation and for releasing said valve for such differential operation, a tool movable vertically in the tubing for controlling the operation of said fastening and releasing means, a flexible line for suspending said tool in the tubing, and means responsive to the pressure of the well fluid elevated in the tubing for operating said flexible connection.

10. In a well flowing apparatus, the combination of, a well tubing string, a nipple adapted to be connected in the tubing, a valve housing communicating with the bore of the nipple and mounted on the nipple, a pressure fluid responsive valve in the housing, an operating member connected with said valve and having a portion exposed in the bore of the nipple, means for fastening the valve, and a tool movable in the bore of the nipple to displace the operating member to release the fastening means and free the valve for operation by pressure fluid and movable from said member to permit the fastening means to lock said valve against pressure fluid actuation.

11. In a well flowing apparatus, the combination of, a well tubing string, a nipple adapted to be connected in the tubing, a valve housing communicating with the bore of the nipple and mounted on the nipple, a pressure fluid responsive valve in the housing, an operating member connected with said valve and having a portion exposed in the bore of the nipple, means for fastening the valve, a tool movable in the bore of the nipple to displace the operating member to release the fastening means and free the valve for operation by pressure fluid and movable from said member to permit the fastening means to lock said valve against pressure fluid actuation, and pressure fluid responsive means at the top of the well connected to the tool for vertically moving the same.

12. In a well flowing apparatus, the combination of, a well tubing and a casing, a lifting fluid inlet valve in the casing connected in the tubing for controlling the admission of fluid from

the casing into the tubing, a spring co-acting with the hydrostatic pressure of the well fluid standing in the tubing for opening said valve, a second and stronger spring disposed to overcome the first spring for closing said valve, and means operable from the top of said well for controlling said second spring to permit said first spring to act.

13. In a well flowing apparatus, the combination of, a well tubing and a casing, a lifting fluid inlet valve in the casing connected in the tubing for controlling the admission of fluid from the casing into the tubing, a spring co-acting with the hydrostatic pressure of the well fluid standing in the tubing for opening said valve, a second and stronger spring disposed to overcome the first spring for closing said valve, means movable independently of the valve for confining the second spring and freeing the first spring for operation, and means operable from the top of the well for actuating said movable means.

14. In a well flowing apparatus, the combination of, a well tubing and a casing, a lifting fluid inlet valve in the casing connected in the tubing for controlling the admission of fluid from the casing into the tubing, a spring co-acting with the hydrostatic pressure of the well fluid standing in the tubing for opening said valve, a second and stronger spring disposed to overcome the first spring for closing said valve, means movable independently of the valve for confining the second spring and freeing the first spring for operation, fluid pressure operating means at the top of the well responsive to the pressure of the elevated well fluid, and a tool suspended in the tubing and operably connected with said operating means for actuating said movable means.

15. In a well flowing apparatus wherein a well casing is provided with a supply of lifting fluid and a well tubing string is mounted therein, the combination of, a lifting fluid inlet valve mounted in the tubing for admitting well and lifting fluid from the casing to the tubing, means controllable from the surface of the well for bringing about the closing and the fastening of said valve, said means also adapted to release said valve, said valve having elements which are responsive to pressure differentials between the well fluid and the lifting fluid and operable when said valve is released, and surface control means operated by pressure fluid for actuating said surface controllable means.

16. In a well flowing apparatus wherein a well casing is provided with a supply of lifting fluid and a well tubing string is mounted therein, the combination of, a lifting fluid inlet valve mounted in the tubing for admitting well and lifting fluid from the casing to the tubing, means controlled from the surface of the well for locking said valve against operation or unlocking said valve where it may be operated, said valve having elements responsive to pressure differentials between the well fluid in the tubing string and the lifting fluid in the casing and operable when said valve is unlocked, and surface control means operated by a pressure fluid for actuating said surface controlled means.

17. In a well flowing apparatus wherein a well casing is provided with a supply of lifting fluid and a well tubing string is mounted therein, the combination of, a lifting fluid inlet valve mounted in the tubing for admitting well and lifting fluid from the casing to the tubing, means controlled from the surface of the well for locking said valve against operation or unlocking said

valve where it may be operated, said valve having elements responsive to pressure differentials between the well fluid in the tubing string and the lifting fluid in the casing and operable when said valve is unlocked, actuating means on the surface for operating said surface controlled means, and surface control means operated by a pressure fluid for operating said actuating means.

18. In a well flowing apparatus wherein a well casing is provided with a supply of lifting fluid and a well tubing string is mounted therein, the combination of, a lifting fluid inlet valve mounted in the tubing for admitting well and lifting fluid from the casing to the tubing, means controlled from the surface of the well for locking said valve against operation or unlocking said valve where it may be operated, said valve having elements responsive to pressure differentials between the well fluid in the tubing string and the lifting fluid in the casing and operable when said valve is unlocked, actuating means on the surface of the well for actuating said surface controlled means, a flow conduit extending to said actuating means for supplying a pressure fluid thereto to operate said actuating means, and surface control means connected to said flow conduit for controlling the flow of a pressure fluid through said conduit to control the operation of said actuating means.

19. The system of flowing wells which includes, a well casing for providing a supply of lifting fluid, a well tubing in the casing for accumulating a quantity of well fluid and serving as a conductor for the well fluid, one or more lifting fluid inlet valves connected to the tubing, means for normally fastening the valve or valves against and releasing said valve or valves for operation by a pressure differential between the well fluid and the lifting fluid, means for utilizing the pressure of the elevated well fluid to control the operation of the fastening and releasing means, means for providing a predetermined amount of mechanical energy which when combined with a hydrostatic pressure of a predetermined quantity of well fluid causes opening of said valve or valves, said fastening means including resilient means for closing said valve or valves, said valves being constructed so that the opening thereof may be controlled by the varying of the pressure of the lifting fluid in the casing.

20. The system of flowing wells which includes, a well casing for providing a supply of lifting fluid, a well tubing in the casing for accumulating a quantity of well fluid and serving as a conductor for the well fluid, one or more lifting fluid inlet valves connected to the tubing, means for normally fastening the valve or valves against and releasing said valve or valves for operation by a pressure differential between the well fluid and the lifting fluid, means for providing a predetermined amount of mechanical energy which when combined with a hydrostatic pressure of a predetermined quantity of well fluid causes opening of said valve or valves, said fastening means including resilient means for closing said valve or valves, said valves being constructed so that the opening thereof may be controlled by the varying of the pressure of the lifting fluid in the casing, means on the surface of the well for controlling the operation of the fastening and releasing means, and means for utilizing the pressure of the elevated well fluid to con-

trol the operation of the surface controlling means.

21. The system of flowing wells which includes, a well casing for providing a supply of lifting fluid, a well tubing in the casing for accumulating a quantity of well fluid and serving as a conductor for the well fluid, one or more lifting fluid inlet valves connected to the tubing, means for normally fastening the valve or valves against and releasing said valve or valves for operation by a pressure differential between the well fluid and the lifting fluid, means for providing a predetermined amount of mechanical energy which when combined with a hydrostatic pressure of a predetermined quantity of well fluid causes opening of said valve or valves, said fastening means including resilient means for closing said valve or valves, said valves being constructed so that the opening thereof may be controlled by the varying of the pressure of the lifting fluid in the casing, means on the surface of the well for controlling the operation of the fastening and releasing means, and means for utilizing the pressure of the elevated well fluid to control the operation of the surface controlling means, said operating means being adjustable to regulate the operation of said surface control means.

22. The system of flowing wells which includes, a well casing for providing a supply of lifting fluid, a well tubing in the casing for accumulating a quantity of well fluid and serving as a conductor for the well fluid, one or more lifting fluid inlet valves connected to the tubing, means for normally fastening the valve or valves against and releasing said valve or valves for operation by a pressure differential between the well fluid and the lifting fluid, means for utilizing the pressure of the elevated well fluid to control the operation of the fastening and releasing means, means for providing a predetermined amount of mechanical energy which when combined with a hydrostatic pressure of a predetermined quantity of well fluid causes opening of said valve or valves, the amount of mechanical energy provided may be varied to control the quantity of well fluid accumulated to regulate the opening of said valve or valves, said fastening means including resilient means for closing said valve or valves, said valves being constructed so that the opening thereof may be controlled by the varying of the pressure of the lifting fluid in the casing.

23. The system of flowing wells which includes, a casing provided with a supply of lifting fluid, a single string of tubing, one or more lifting fluid inlet valves connected to the tubing for admitting lifting fluid from the casing to the tubing, said valves adapted to be selectively and intermittently operated, means controlled from the surface of the well for locking said valves against operation, said means being adapted to unlock said valves, said valves having elements responsive to pressure differentials between the well fluid and the lifting fluid which are operable when said valves are unlocked.

24. The system of flowing wells which includes, a casing provided with a supply of lifting fluid, a single string of tubing, a plurality of fluid inlet valves mounted in the tubing for admitting lifting fluid from the casing to the tubing, said valves adapted to be selectively and intermittently operated, and means controlled from the surface of the well for locking said valves against operation, said means being adapted to selectively

tively release any of said valves, said valves having elements responsive to pressure differentials between the well fluid and the lifting fluid which are operable when any of the valves are released.

25. In a well flowing apparatus wherein a well casing is provided with a supply of lifting fluid and a well tubing string is mounted therein, the combination of, a lifting fluid inlet valve mounted in the tubing for admitting well and lifting fluid from the casing to the tubing, said valve being adapted to be intermittently operated, means controlled from the surface of the well for bringing about the closing and the fastening of said valve, said means also adapted to release said valve, said valve having elements which are responsive to pressure differentials between the well fluid and the lifting fluid and operable when said valve is released, and surface control means operated by a pressure fluid for actuating said surface controlled means.

26. In a well flowing apparatus wherein a well casing is provided with a supply of lifting fluid and a well tubing string is mounted therein, the combination of, a plurality of lifting fluid inlet valves mounted in the tubing for admitting lifting fluid from the casing to the tubing, said valves adapted to be selectively and intermittently operated, means controlled from the surface of the well for bringing about the locking of said valves, said means also adapted to unlock said valves, said valves having elements which are responsive to pressure differentials between the well fluid and the lifting fluid and these elements are operable when said valves are unlocked, and surface control means operated by a pressure fluid for actuating said surface controlled means, said surface control means having regulating means to control the operation thereof.

27. A system of flowing wells which includes, a well casing provided with a supply of lifting fluid above the liquid therein, a single string of well tubing in said casing, whereby columns of well fluid may accumulate in the well casing and tubing, means for controlling the admission of fluid from the casing to the tubing, means for controlling from the surface of the well the fastening and releasing of the admission controlling means, said admission controlling means when released being actuated by a pressure differential between the well fluid and the lifting fluid to admit lifting fluid to the tubing to elevate the well fluid to the top of the well, and means for utilizing the elevated well fluid to control the surface control means to bring about the closing of the admission controlling means to terminate the admittance of lifting fluid and to lock said means against reopening.

28. A system of flowing wells which includes, a well casing, a single string of well tubing in said casing, whereby columns of well fluid may accumulate in the well casing and tubing, one or more pressure differential operated lifting fluid inlet valves mounted in the tubing, means for normally fastening said inlet valve or valves against operation by a pressure differential, means for releasing said valve or valves for opening by a pressure differential, and means for utilizing the pressure of the elevated well fluid to control the releasing and fastening means.

29. A system of flowing wells which includes, a well casing, a well tubing in the well casing, a lifting fluid pressure differential operated valve connected to the well tubing, means for normally fastening the valve against operation by

or for releasing said valve for opening by a pressure differential, means for utilizing the elevated well fluid to control the fastening and releasing means, and means for providing a predetermined amount of mechanical energy which when combined with a hydrostatic pressure of a predetermined quantity of well fluid causes opening of said valve, said fastening and releasing means including resilient means for closing the valve.

30. In a well flowing apparatus wherein a well casing is provided with a supply of lifting fluid and a well tubing is mounted therein, the combination of, a lifting fluid inlet valve connected to the tubing for admitting well and lifting fluid from the casing into the tubing, means controlled from the surface of the well for fastening said valve against operation or releasing said valve where it may be operated, said valve having elements responsive to pressure differentials between the well fluid in the tubing and the lifting fluid in the casing and operable when said valve is released, and surface control means operated by a pressure fluid for actuating said surface controlled means.

31. In a well flowing apparatus wherein a well casing is provided with a supply of lifting fluid and a well tubing string is mounted therein, the combination of, a lifting fluid inlet valve connected to the tubing for admitting well and lifting fluid from the casing to the tubing, means controlled from the surface of the well for fas-

tening said valve against operation or releasing said valve where it may be operated, said valve having elements responsive to pressure differentials between the well fluid in the tubing and the lifting fluid in the casing and operable when said valve is released, an actuator on the surface for operating said surface controlled means, and surface control means operated by a pressure fluid for controlling the operation of said actuator.

32. In a well flowing apparatus wherein a well casing is provided with a supply of lifting fluid and a well tubing is mounted therein, the combination of, a lifting fluid inlet valve connected to the tubing for admitting well and lifting fluid from the casing to the tubing, means controlled from the surface of the well for locking said valve against operation or unlocking said valve where it may be operated, said valve having elements responsive to pressure differentials between the well fluid in the tubing and lifting fluid in the casing and operable when said valve is unlocked, actuating means on the surface of the well for actuating said surface controlled means, a flow conduit extending to said actuating means for supplying a pressure fluid thereto to operate said actuating means, and surface control means connected to said flow conduit for controlling the flow of a pressure fluid through said conduit to control the operation of said actuating means.
